UNITED STATES PATENT OFFICE.

MOSES A. WOOLDRIDGE, OF WYACONDA, MISSOURI.

RAILROAD GRADE CROSSING.

Application filed June 18, 1928. Serial No. 286,243.

This invention relates to an improvement in railway grade crossings which may be readily installed for a permanent way or as a temporary crossing.

5 The invention consists in providing between the rails metallic containers or receptacles which are of a suitable size with respect to the distance between the rails and the height thereof so as to afford the proper 10 clearance for the flanges of the wheels of a train and provide a crossing which will be on the same level with the rails and permit easy travel across the tracks, suitable means being provided for insulating the containers 15 from the rails and fastening them in place. Located outside of the track and along the outer sides of the outermost rails are containers or receptacles for forming the proper approach for the crossing. The 20 containers located along the sides of the tracks and between the rails are to be filled with any suitable material which may be suitable for grade crossings, such as ground rock, concrete, asphalt and the like.

25 A further object of the invention is to provide means for fastening the innermost and outermost containers to the base flange of the rails for holding the containers upon the ties and against longitudinal and lateral 30 movement.

The invention consists of certain novel features of construction and combinations of parts which will be hereinafter described and pointed out in the claims:

35 In the accompanying drawings:

Figure 1 is a top plan view showing one form of the invention applied in position,

Figure 2 is a longitudinal vertical sectional view along the line 2—2 of Figure 1,

Figure 3 is a vertical transverse sectional view on the lines 3—3 of Figure 1,

Figure 4 is a top plan view showing the innermost containers made in sections,

45 Figure 5 is a bottom plan view in detail showing the manner of fastening the containers to the rails, and

Fig. 6 is a perspective view of the clip and wedge.

In the drawing the invention has been 50 shown applied to a single track highway, although it is to be understood that it is applicable to any crossing regardless of the number of tracks employed at the crossing.

The usual cross ties 10 have supported 55 thereon rails 12. Located between the rails 12, as illustrated in Figure 1, are two metallic containers 13—13. These containers may be made of any suitable metal and are preferably rectangular in shape, having side 60 walls 14 and a bottom 15. Connected to the bottom 15 at suitable intervals are a plurality of ribs 16, extending longitudinally of the containers for supporting the containers upon the ties 10. These ribs 65 are provided with base flanges 17. Each of the containers 13—13 is provided along its longitudinal edges, forming a continuation of the bottom 15, with laterally extending flanges 18, which project beneath 70 the ball or tread of the rails 12.

Interposed between the web 19 of the rails and the outer edge of the flanges 18 are strips of insulation 20, for insulating the containers from the rails and thereby preventing these containers from interfering with the rails when employed as a means of conducting an electric current.

75 Wedges 21 are provided for fastening and holding the containers in position between the rails. These wedges 21 consist of plates of sufficient length for securing and fastening the containers between the rails and being provided with longitudinal 80 grooves or recesses 22, for the reception of the flanges 18 of the containers. The upper and lower edges of the plates 21 are bent or curved outwardly so that they will project toward the web 19, of the rails 12 and engage the base flange 23 beneath the ball or 85 tread of the rail.

The wedges 21 are driven into place between the insulation 20 and the flanges 18 causing an engagement between the rails 90

and the flanges 18, for preventing any vertical or longitudinal movement of the containers or receptacles. These wedge plates 21 will be made of some suitable resilient material which will permit of their being driven into place and to engage the ball and flange of the rails to firmly lock the containers in place.

Located along the outer sides of the rails 12 are smaller containers or receptacles 24, which are supported by means of ribs 25, having base flanges 26, which rest upon the ties. The innermost rib 25 is not provided with a base flange and the rib rests upon the base flange 23 of the rail 12, so that the containers can be located in close proximity to the outer surface of the ball tread of the rails.

The construction illustrated in Figure 4 is similar to the construction shown in Figure 1 and differs therefrom only in that the innermost containers are made in two sections instead of one. The various sections or containers are preferably constructed in four, six and eight feet lengths in accordance with the requirements and as many of these containers as are required may be arranged end to end between and along the rails for providing a crossing of any given length. Each of the containers will be filled with some suitable material such as ground rock, concrete, asphalt or the like for forming a satisfactory road surface.

The various containers or receptacles are secured in position by means of clips or hooked plates 27. The plates 27 are provided with hooked ends 28, one of which will engage a base flange 17 of the rib 16 of the innermost container or containers in accordance with the construction employed, as illustrated in Figures 1 and 4. The plates 27 extend beneath the base flange 23 of the rail 12 and the other hooked end 28 of the plate will engage the base flange 23.

A wedge 29 is then driven between the hooked end 28 and the outer edge of the base flange 23 for drawing the container toward the rail and securely clamping it upon the ties. These plates 27 are located at suitable intervals of near each end of the containers for fastening them to the rail. The outermost container or container 24 are similarly held by means of the plates 27 with hooked end 28 engaging the innermost base flange 23 of the rail and extending then beneath the rail and container 24 with the other hooked end 28 engaging the outermost base flange 26 of the rib 25; and a wedge 30 is driven between the hooked end and flange 26 for forcing the receptacle or container 24 against the rail and clamping it upon the ties.

By providing these clamping plates 27 at suitable intervals the containers 13 and 24

may be fastened to the rails and held rigidly upon the ties without the danger of movement either longitudinally or laterally due to any vibration which may be imparted to them by the passing trains.

At the ends of the crossing the containers are provided with guard plates 31, which plates are provided with downturned edges at their upper ends for engaging the ends of the containers 13 and 24. These guard plates project downwardly at an obtuse angle and are fastened to a tie 10, by means of spikes or screws 32. These guard plates afford protection to any railway equipment which may be hanging from the train to prevent its being caught by the containers.

The containers 13, illustrated in Figure 1, together with the flanges 18 are of greater width than the distance between the treads of the adjacent rails; but the containers are of such width that the flanges may be inserted beneath the tread and lowered into position between the rails without the necessity of removing a rail to place the containers in position.

Claims:

Having described my invention what I claim as new and desire to secure by Letters Patent is:

1. In a railway crossing, the combination with the rails of a track having treads, of metallic containers interposed between the rails and having a suitable road filler deposited therein, flanges on said containers projecting beneath the treads of the rails, and metallic wedges interposed between the flanges and the rails for fastening the containers in position.

2. In a railway crossing, the combination with the rails of a track having treads, of metallic containers interposed between the rails and having a suitable road filler deposited therein, flanges on said containers projecting beneath the treads of the rails, and resilient metallic wedges between the rails and flanges for maintaining the containers in position.

3. In a railway crossing, the combination with the rails of a track having treads, of metallic containers interposed between the rails and having a suitable road filler deposited therein, flanges on said containers projecting beneath the treads of the rails, and metallic plates driven between the flanges and the rails for fastening the containers in position, said plates being provided with longitudinal grooves for receiving the flanges of the containers and having the edges thereof extending outwardly for engaging the tread of the rails for securing and holding the containers in position.

4. In a railway crossing, the combination with the rails of a track having treads, of containers interposed between the rails and located along the sides of the rails and hav-

ing a suitable filler therein, ribs for supporting said containers, and clamping plates having hooked ends for engaging the rails and ribs of the containers for fastening the containers in position with respect to the rails.

5. In a railway crossing, the combination with the rails of a track having treads, of metallic containers located between said rails and provided with flanges projecting beneath the tread of said rails, means for fastening the flanges to the rails and means for fastening the containers to the rails.

6. In a railway crossing, the combination with the rails of a track having treads, of containers located between said rails provided with flanges projecting beneath the tread of said rails, means for fastening the flanges to the rails, containers located adjacent the outer sides of said rails and means for removably connecting the various containers to the rails for maintaining the containers in position with respect to the rails.

MOSES A. WOOLDRIDGE.
